UNITED STATES PATENT OFFICE

156,792

EGG BEATER

Thomas J. White, Kirkwood, Mo.

Application October 25, 1947, Serial No. 142,144

Term of patent 3½ years

(Cl. D44—1)

To all whom it may concern:

Be it known that the undersigned, Thomas J. White, a citizen of the United States, residing in Kirkwood, St. Louis County, State of Missouri, has invented a new, original, and ornamental Design for an Egg Beater, of which the following is a specification, reference being had to the accompanying drawing, forming a part thereof, in which:

Fig. 1 is a front elevation of an egg beater, showing my new design;

Fig. 2 is a side elevation of Fig. 1, taken from the right side of Fig. 1, the beater unit being omitted for convenience of illustration; and

Fig. 3 is an angular view wherein the casing portion is turned something over 90° from the position of Fig. 1 to show the design below the handle, the beater unit being omitted for convenience of illustration.

A view of the side opposite that shown in Fig. 2 would be the same as Fig. 2.

The essential features of my design reside in those portions shown in full lines.

I claim:

The ornamental design for an egg beater, substantially as shown and described.

THOMAS J. WHITE.
